RUBBER BALL

Fred T. Roberts, Malone, N. Y.

Application October 6, 1933, Serial No. 692,388
Renewed June 12, 1937

16 Claims. (Cl. 273—61)

This invention relates to a ball, suitable for use in athletic games, particularly the type used for playing tennis and similar games.

My copending application Serial Number 504,767, filed December 26th, 1930 (now Patent No. 1,964,008), of which the present invention is an improvement, shows, describes and claims a ball having on the interior thereof ribs integral with the wall of the ball, serving to resist inward distortion of the wall and thus giving the ball resilience. In that application, however, the ribs are shown in the form of meridians extending from either the poles or small polar circles. I found, however, that such ribs are farther apart than desirable in the equatorial region of the ball, or if they are made close enough together in this region there is too great a concentration of rubber near the poles. In either case the degree of rebound of the ball is variable over a surface, thus interfering with its employment where accuracy of reaction is required.

In the present invention I provide ribs on the interior of the ball integral with the wall, as claimed in my prior application, but I now arrange these ribs to form a network on the inside of the ball, thus making the spherical surface more uniformly braced on the interior.

A further advantage of this application in addition to its uniformity and increased liveliness lies in the fact that it may be inflated to retain its region between the ribs' sphere with a lower internal pressure than heretofore. This not only simplifies the operation of manufacture but is an advantage in the durability of the balls, as there is less leakage and hence, they remain lively for a longer period of time.

In making my improved ball, I may form the network of ribs on the interior surface of complimentary halves, which may be semi-cured and later placed together and joined to form a complete ball with any desired degree of inflation.

I prefer to make the ball by the method herein disclosed, of forming ribs on the external surface of the halves of the ball, curing the halves sufficiently to give the rubber a permanent set, then "introverting" the halves, or turning them inside out, and joining them together by any well-known method.

My invention comprises also applying an exterior wrapping to such a ball, tending to compress the ball and counteracting the expanding force. A ball constructed in this novel manner rebounds much more quickly after striking a surface, and is more satisfactory where a very lively ball is required.

My invention is illustrated in the drawings hereof, which disclose the ball in various stages of manufacture and in various modifications, and thereby illustrate also the method of manufacture.

In the drawings Fig. 1 is a view of half of the ball with the ribs formed on the outer surface thereof, preliminary to introverting; Fig. 2 is a view similar to Fig. 1 and showing an alternative method of arranging the ribs on the ball; Fig. 3 is a view of the half-ball shown in Fig. 1, after it has been turned inside out; Fig. 4 is a view, partly in section of a ball formed by joining two halves, like Fig. 3, and shows a wrapping which may be applied outside of such ball, while Fig. 5 is a sectional view through the finished ball of Fig. 4, showing a cover cemented in place; Fig. 6 represents a standard ball to which the wrapping has been applied; Fig. 7 is a view, partly in section, of a ball of the character described, before said ball has been wrapped, while Fig. 8 is a view partly in section of the ball of Fig. 7, after the same has been wrapped and completed.

The halves of the ball, molded as in Fig. 1 or Fig. 2, or some similar manner, are cured sufficiently to cause a permanent set in the rubber. I have found that a three-fourths cure will accomplish the result desired. The halves are then introverted as shown in Fig. 3, and joined together in an atmosphere of compressed air of comparatively low pressure, at which time the ball receives a finish cure. It is also possible, however, to completely cure the halves in the position shown in Figs. 1 or 2, and thereafter turn the halves inside out, place the free edges together and cold-cure the joint between them. Also, the inflation may be by other well-known means, if desired.

The ball of which half is shown in Figs. 1 and 3 has a wall 18 which is provided with substantially meridian ribs 10, latitudinal ribs 11, a middle or equatorial rib 13, and diagonal ribs 12, running from the junction point of meridian ribs with the latitudinal ribs, to a point on the equatorial rib substantially midway between the meridian ribs. The ribs are formed in the mould which forms the ball so that the ribs are integral with the wall 18. The meridian ribs may join at the pole 20, or may be connected to a polar circle as shown in my Patent No. 1,964,008.

In the modification shown in Fig. 2, the meridian ribs 10, the latitudinal ribs 11, and the equatorial rib 13 are similar to those in Fig. 1, but in this case the meridian ribs extend only from the pole to the latitudinal ribs 11. The diagonal ribs 12

14 extend from these junction points equiangularly toward each other to meet at the equatorial rib. This arrangement is substantially equivalent to Fig. 1, with the portions 15 of the meridian ribs left out. In any case, the arrangement of the ribs should preferably be such as to divide the surface of the ball into substantially equal unsupported portions, such as are indicated by the character 16 in Fig. 1 and 17 in Fig. 2. This 10 gives a uniform bounce regardless of the spot where the ball receives a blow.

As pointed out in my Patent No. 1,964,008, when the ball is formed in the above-described manner, (the ribs being first formed on the outside 15 of the ball, which is later introverted to place the ribs upon the inside) the ribs are thus finally constrained into a smaller space than that in which they were given the original cure, and are thus given a permanent compression. This causes 20 the ribs to exert a spring-like action in the interior of the ball and greatly increases the resilience thereof.

When joining together the two halves of the ball to form the completed ball, it is preferable 25 that similarly situated ribs on the two halves of the ball register to form a continuous pattern as shown in Figs. 4 and 5. However, the equatorial rib overcomes the necessity for such accurate registration as is required in my former ball. 30 The equatorial rib portions 13 formed on the halves will preferably be of slightly less thickness than the other ribs, as these two ribs, when placed together should form a rib substantially corresponding to all the other ribs of the ball to 35 promote uniformity.

The halves of the ball may be joined together in an atmosphere of compressed air in the well-known manner if desired, and thus the pressure within the ball may be nicely controlled. I have 40 found that a ball formed with the network of ribs as above described makes a very lively ball, even though just sufficient air is placed therein to retain its shape.

A more lively, though more expensive, ball may 45 be made if sufficient pressure is placed within the ball to slightly distend the unsupported portions 16 of the ball surface beyond the normal spherical contour of the ball. An outside wrapping of thin strips of cured rubber 30 may then be 50 wrapped tightly around the exterior of the ball, forcing the distended portions 16 back into their normal contour. The method of thus wrapping a ball is disclosed and claimed in a copending application of mine. Such a ball may then be 55 finished by cementing the ball over the wrapping as at 31, covering it with felt, indicated at 32 and giving it a final cure to cure the cement.

In making my improved ball, I may take an 60 inflated spherical ball, having smooth interior and exterior surfaces, and wrap the same with thin rubber bands 30, as indicated in Fig. 6. Such a wrapping with any thin rubber band will 65 improve the ball, but preferably I use a very wide and thin, cured rubber strand which is wrapped tightly about the ball in every direction and in a sufficient layer to create a compressive effect upon the ball.

70 Preferably, however, I take in place of a plain hollow ball one having internal ribs, similar to that above described. These ribs may be formed on the interior surface of the ball originally, but preferably I use the method disclosed in which the ribs are first molded upon the exterior of the halves of the ball, and sufficiently cured to give 75 the rubber a permanent set. As disclosed in

the said applications, the halves may be semi-cured to the proper point and finish cured when joined together. Or the halves may be completely cured and joined together by cold curing. In either case the halves are turned inside out after 5 the first curing and secured together, thus placing the internal ribs under compression.

A ball, having internal ribs 10 and 11, is shown in Fig. 7, there being unsupported wall surfaces 16 between such ribs. In one method of making this ball, after the halves are completed, their free edges are joined together in an atmosphere of compressed air sufficient to distend the unsupported portions 16 of the walls of the ball in the manner shown at 24. The best results 10 are secured if the pressure is not sufficient to expand the portion of the ball carrying the ribs. This is particularly true if the ball is formed according to the method disclosed, where the ribs are under compression. It will be obvious that 20 any expansion of the ball which materially extended these ribs would tend to nullify the expanding effect or resilient action of the ribs.

The ball of Fig. 7 may then have a wrapping 25 of rubber bands 30 applied as described in connection with Fig. 1, thus constricting the distended portions 24 of the unsupported walls of the ball back to their spherical shape, as shown in Fig. 8. This provides an extremely lively ball, as the internal compressed ribs and the internal 30 fluid pressure tend to expand the ball, while the wrapping of rubber bands creates a force in the opposite direction.

The ball of Fig. 8 may then be finished by applying a coating of cement 31 outside the wrapping, and a cover of felt 32 over all, and the ball may then be placed in a mold for a final 35 curing sufficient to cure the cement coating and hold the cover in place.

While the ball of this invention is not limited 40 to any particular dimensions, a tennis ball, under the currently accepted rules, should have an external diameter of $2\frac{1}{16}$ inches. In making such a ball, by the preferred method illustrated 45 in Figs. 7 and 8, I propose to first mold a ball half having a main wall about $\frac{1}{16}$ inch in thickness, the mould having an external diameter of $2\frac{1}{16}$ inches, this defining the dimension of the main wall of the ball. The ribs will be $\frac{1}{8}$ inch outside of this or $2\frac{1}{16}$ inches across the outside 50 surfaces of the ribs. Then this half is inverted and joined to another correspondingly formed half in an atmosphere of compressed air, with just sufficient pressure to slightly bow out the thin wall between the ribs but not inflating the ball to over-size. I then wrap the ball so that the bowed thin places are brought down to the spherical surface of the ball. I then cover the ball with cement, place over this felt, and put the entire ball back into a mould $2\frac{1}{16}$ inches in 55 diameter and cure it enough to vulcanize the cover of the ball. The wrapping, cement and felt add $\frac{1}{16}$ inch to the outside radius of the main wall of the ball.

This makes a ball having internal ribs which 65 were molded so that their original outer surface before introversion had a diameter of $2\frac{1}{16}$ inches, but which when introverted to place the ribs inside the ball have an internal diameter of $2\frac{1}{16}$ inches. Accordingly, the original set of the 70 ribs is retained, and thus the outward spring of these ribs, caused by their being compelled to occupy a less space than when formed, gives the ball the high resilience desired.

While this application is concerned with balls 75

having an internal ribbed structure, (with or without a wrapping of elastic strands), reference is made to my copending application Serial No. 228,093, filed September 2, 1938, for claims on 5 a ball having a central sphere with an elastic winding thereon irrespective of the internal construction of such sphere. Reference is also made to my copending application Serial No. 112,572, filed November 24, 1936, for the method of making the ball herein disclosed.

I claim:

1. A hollow rubber ball having internal fluid pressure, ribs on the interior surface of said ball spaced with respect to each other to form spherical triangles, and an exterior covering of tightly wrapped rubber bands to reinforce the portions between the ribs.

2. A hollow spherical rubber ball having a wall, meridian ribs integral with said wall, a network 20 of diagonal ribs on the interior surface of said wall and integral therewith, there being unsupported portions of said wall between said ribs, fluid pressure within said ball adapted to distend said portions of the wall beyond the normal spherical surface of said ball, and a wrapping 25 of rubber bands on the exterior surface of said ball to reinforce said portions.

3. A hollow rubber ball having a wall, a network of intersecting meridian ribs and latitudinal ribs intersecting each other, on the interior surface of said wall and integral therewith, there being unsupported portions of said wall between said ribs, fluid pressure within said ball adapted to distend said portions of the wall beyond the normal spherical surface of said ball, a wrapping 35 of rubber bands on the exterior surface of said ball, to reinforce said portions a coating of cement over the wrapping and a felt cover outside the cement.

4. A hollow, rubber ball, comprising a wall, 40 internal ribs on the inside of said wall, compressed to a greater extent than the said wall, whereby an indented outer surface is formed, and means on the exterior of said wall to compress the upstanding portions of the ball surface inwardly, whereby said ball attains a smooth, 45 spherical shape.

5. A hollow, rubber ball, comprising a wall, 50 internal ribs intersecting at points spaced over the entire surface on the inside of said wall and compressed to a greater extent than the wall, whereby said wall is distended from spherical shape, and means on the exterior of said wall to compress the extended portion inwardly to cause the ball to assume a smooth, spherical 55 shape.

6. A hollow, spherical, rubber ball, comprising a wall, internal ribs on the inside of said wall, compressed to a greater extent than the wall, 60 whereby humps are formed between the rib portions and adjacent wall portions, and the ball is distorted from a true spherical shape, and means on the exterior of said wall to compress the same inwardly, whereby said ball attains a smooth, spherical shape.

7. A hollow rubber ball comprising a wall, internal ribs on the inside of said wall compressed to a greater extent than said wall, whereby the

exterior of said wall is distorted from a true spherical surface into a plurality of depressions between respective ribs, and means on the exterior of said wall to compress the same inwardly, whereby said wall attains its smooth spherical 5 surface.

8. A hollow rubber ball having a wall with two pole points, several arcuate ribs extending in meridional fashion from each pole point, said ribs having their outer convex boundaries joining 10 the inner surface of the wall and their inner concave boundaries unattached, latitudinal ribs extending around said wall on the inside thereof and intersecting said pole ribs, said latitudinal ribs extending over substantially the entire ball 15 surface, said intersections occurring at points spaced over the entire surface of the ball, and especially intermediately of the equitorial plane of the ball and each pole point.

9. A hollow rubber ball, ribs on the interior 20 surface of said ball, spaced with respect to each other to form spherical triangles, and an exterior covering of tightly wrapped rubber bands to reinforce the portions between the ribs.

10. A hollow, spherical rubber ball, having a 25 wall, meridian ribs and diagonal ribs on the interior surface of said wall and integral therewith, there being unsupported portions of said wall between said ribs and a wrapping of rubber bands on the exterior surface of said ball to 30 reinforce said portions.

11. A hollow, rubber ball, having a wall, a network of meridian ribs and latitudinal ribs intersecting each other on the interior surface of said ball and integral therewith, there being unsupported portions of said ball between said ribs, a 35 wrapping of rubber bands on the exterior surface of said ball to reinforce said portions, a coating of cement over said wrapping and a felt cover outside said cement.

12. A hollow rubber ball, spaced ribs on the 40 interior surface of said ball and an exterior covering of tightly wrapped rubber strands to reinforce the portions between said ribs.

13. A hollow rubber ball, spaced ribs on the 45 interior surface of said ball, an exterior covering of tightly wrapped rubber strands to reinforce the portions between said ribs, and a felt cover secured to said ball outside the covering of rubber strands.

14. A hollow rubber ball having internal rubber 50 ribs compressed to a greater extent than the wall of the ball, and a wrapping of stretched rubber strands on the exterior of the wall.

15. A hollow rubber ball having internal rubber 55 ribs integral with the wall of the ball but compressed to a greater extent than the wall of the ball and a wrapping of thin elastic strands on the exterior of the wall.

16. A hollow rubber ball having in its interior 60 circular ribs in the position of parallels of latitude and ribs extending at an angle thereto, the latter ribs being under longitudinal compression and serving to support the ball surface at regular intervals at the edges of various areas thereof and a wrapping of stretched elastic strands about 65 the ball which compress said areas.

FRED T. ROBERTS.
